(57) **CLAIM**

The ornamental design for a tablet computing device, as shown and described.

DESCRIPTION

FIG. 1 is a front perspective view of a tablet computing device showing our new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof;

FIG. 8 is a top plan view thereof;

In the first embodiment, the stippling on the back and sides of the tablet computing device indicates a first, textured surface finish, the oblique lines on the front of the tablet computing device indicates a second, glass-like surface finish, and the omission of stippling and oblique lines on a bezel disposed around a perimeter of the back of the device (best shown in FIGS. 3 and 4) indicates a glossy surface finish.

FIG. 9 is a front perspective view of a second embodiment of a tablet computing device;

FIG. 10 is a rear perspective view of FIG. 9;

FIG. 11 is a front elevational view of FIG. 9;

FIG. 12 is a rear elevational view of FIG. 9;

FIG. 13 is a right side elevational view of FIG. 9;

FIG. 14 is a left side elevational view of FIG. 9;

FIG. 15 is a bottom plan view of FIG. 9; and,

FIG. 16 is a top plan view of FIG. 9.

The broken lines indicate unclaimed portions and form no part of the claimed design.
